UNITED STATES PATENT OFFICE.

DANIEL CATER, OF SILVER LAKE, TEXAS.

DESIGN FOR A RAILROAD-BRACE.

SPECIFICATION forming part of Design No. 29,445, dated October 4, 1898.

Application filed September 2, 1898. Serial No. 690,139. Term of patent 7 years.

To all whom it may concern:

Be it known that I, DANIEL CATER, a citizen of the United States, residing at Silver Lake, in the county of Van Zandt and State 5 of Texas, have invented and produced a new and useful Design for a Railroad-Brace, of which the following is a specification.

This invention is a new and useful design for a railroad-brace, the essential feature residing in the peculiar shape and configuration of the said brace.

The drawings hereto annexed fully illustrate my invention, in which—

Figure 1 is a perspective view of a rail- 5 brace constructed in accordance with my design, and Fig. 2 is a transverse vertical section.

Referring to the drawings in detail, A represents the body of the brace, the upper edge 0 thereof being curved or bent upwardly, as

shown at B. The body of the brace is also curved at its lower edge, as shown at C, and D represents, essentially, rectangular-shaped tongues projecting from the lower edge of the body of the brace, said arms or tongues being 25 slightly longer than they are wide, and E represents circular openings arranged in the form of the tongue.

The advantages and utility of a brace constructed in accordance with my design are 30 apparent to every one.

Having thus described my invention, what I claim as new, and desire to secure by Letters Patent, is—

The design for a railroad-brace, substantially as herein shown and described.

DANIEL CATER.
